UNITED STATES PATENT OFFICE.

RUDOLF SCHRÖDER, OF LEIPZIG, GERMANY.

CLOTHES-HANGING HOOK.

1,065,175.

Specification of Letters Patent Patented June 17, 1913.

Application filed May 14, 1912. Serial No. 697,315.

To all whom it may concern:

Be it known that I, RUDOLF SCHRÖDER, a subject of the King of Saxony, residing at Leipzig, in Germany, have invented a certain new and useful Improvement in Clothes-Hanging Hooks, of which the following is a specification.

The present invention relates to clothes-hanging holders provided with coin-operated locking mechanism for retaining articles of apparel hung thereon.

The invention is illustrated in the accompanying drawing, in which—

Figure 1 is a side view of the device partly in section, and with parts of the locking mechanism omitted. Fig. 2 is a rear view with the back of the lock case removed, showing the locking mechanism in operation. Fig. 3 is a rear view, showing the locking mechanism in the course of the unlocking operation, and Fig. 4 is a rear view, showing the locking mechanism in the open position, with the key retained in the lock.

In the drawing *a* represents a fixed hat peg, and *b* a fixed clothes peg, *d* *d*¹ being the limbs of a substantially S-shaped locking member which is pivoted at *g* and the ends of which are adapted to abut against the ends of the pegs *a* and *b*. A spring *f* bearing against the limb *d*¹ tends to hold the locking member in the open position indicated by dotted lines in Fig. 1. The limb *d* has a rearward projection *d*² which projects through a slot *h* into the casing *k*, and is adapted to coact with a double armed locking lever *i*, *i*¹ rotatably mounted on a spindle *m* inside the casing. A spring *w* bears against the lever arm *i*¹, and the arm *i* is provided above the pivot *m* with a curved shoulder *i*², against which the tail *n*¹ of a double armed tumbler *n*, pivoted at *o*, is adapted to fit and thereby prevent movement of the said lever *i*, *i*¹. Above the locking lever *i*, *i*¹ is pivoted, at *s*, a bell crank lever *p*, *p*¹, the arm *p*¹ of which depends into the coin chute *A*, the other arm *p* having a hooked end *p*² adapted to engage a notch *r*¹ in a push key *r* and lock the key after it has been inserted into the lock. A spring *x* normally holds the lever *p*, *p*¹ in the position in which it is shown in Fig. 2.

Pivoted at *u* to the coin chute is a double armed lever *t*, *t*¹, the arm *t* of which terminates in the path of the above mentioned projection *d*² of the member *d*, *d*¹, and the arm *t*¹ has a bent up end *t*² projecting

through a slot *v* into the coin chute. A spring *q* tends to thrust the arm *t* downward. An abutment *e* for the inserted coin *z* is provided below the slot *v*.

The action of the device is as follows: When articles of apparel have been hung on the pegs *a*, *b* and the locking member *d*, *d*¹ is in operation, as shown by solid lines in Fig. 1, the parts inside the lock casing *k* occupy the position shown in Fig. 2, the arm *i*¹ of the locking lever *i* being thrust behind the projection *d*², so that the member *d*, *d*¹ cannot be rocked into the position indicated by broken lines in Fig. 1; the arm *p* of the bell crank lever *p*, *p*¹ is held in horizontal position by the spring *x*, and the arm *t* of the lever *t*, *t*¹ is lifted by the projection *d*². For unlocking the device, the push key *r* is inserted into the case, whereby the arm *p* is raised, and the locking lever *i* and tumbler *n* are rocked about their pivots *m*, *o* as shown in Fig. 3, so that the arm *i*¹ is removed from the inward path of the projection *d*² and allows the member *d*, *d*¹ to be rocked by the spring *f* into the position indicated in Fig. 1 by broken lines. At the same time the key *r* is locked by the hooked end or nose *p*² of the lever *p*. For again locking the member *d*, *d*¹ the key *r* must be released. For this purpose a coin *z* is dropped into the chute so that it rests on the abutment *e* between the lower ends of the arms *p* and *t*¹ (Fig. 4). The locking member *d*, *d*¹ is then rocked into locking position by hand, whereby the projection *d*² is caused to rock the lever *t*, *t*¹, so that the arm *t*¹ pushes the coin *z* against the lever arm *p*¹ and causes the arm *p* to release the key *r*. This enables the locking lever *i*, *i*¹ to be rocked by the spring *w*, so that the arm *i*¹ lies behind the projection *d*² and retains the member *d*, *d*¹ in locking position, the lever *i*, *i*¹ being locked by the tumbler *n*.

What I claim as my invention and desire to secure by Letters Patent of the United States is:—

In combination, a case having a key-hole and a slot; a clothes hook fixed to said case; a movable hook-closing member having a projection adapted to enter said slot; a locking lever in said case arranged to be disabled by insertion of a key through said key-hole; a spring whereby said locking lever is normally held in the path of said projection and prevents movement of the hook-closing member to its inoperative position;

a coin-chute; a key-retaining lever having one arm in said coin-chute and one arm arranged to engage a key inserted through said key-hole; and a bell-crank having one arm in said coin-chute and one arm in the path traversed by said projection during the movement of the hook-closing member to its operative position, the bell-crank arm in the coin-chute being adapted to actuate the key

retaining lever by means of an inserted coin, 10 for the purpose set forth.

In witness whereof I have signed this specification in the presence of two witnesses.

RUDOLF SCHRÖDER.
